UNITED STATES PATENT OFFICE.

HERMINE GUIDEZ, OF NEW YORK, N. Y.

DESIGN FOR A PATTERN FOR DRESS-SKIRTS.

SPECIFICATION forming part of Design No. 35,846, dated April 1, 1902.

Application filed February 26, 1902. Serial No. 95,827. Term of patent 8½ years.

To all whom it may concern:

Be it known that I, HERMINE GUIDEZ, a citizen of the United States, residing in New York, borough of Manhattan, and State of New York, 5 have invented and produced a new and original Design for Patterns for Dress-Skirts, of which the following is a specification, reference being had to the accompanying drawings, forming part thereof, in which—

10 Figure 1 is a side elevation of a dress-skirt pattern, showing my new design; and Fig. 2 is a horizontal section of the same on line 2 2, Fig. 1.

As shown in the drawings, the skirt-body *a* is provided near the girdle-piece *a'* with parallel bands *b b*, which extend in downward direction from the rear toward the front of the skirt, while similar parallel bands *b' b'* extend from the girdle-piece *a'* in downward 15 direction to the bottom of the skirt. Undu-

lating bands *b²* extend from the longitudinal rear bands *b'* across and toward the front of the skirt. Another band *b³* extends around the bottom of the skirt. The bands *b b' b² b³* are ornamented by undulating or zigzag trimmings. The longitudinal and transverse bands divide the skirt into different sections. 25

Having described my invention, what I claim as new, and desire to secure by Letters Patent, is—

30 The design for a pattern for dress-skirts, as herein shown and described.

In testimony that I claim the foregoing as my invention I have signed my name in presence of two subscribing witnesses.

HERMINE GUIDEZ.

Witnesses:

PAUL GOEPEL,

HENRY SUHRBIER.
